UNITED STATES PATENT OFFICE.

OLIVER M. BURTON, OF CHICAGO, ILLINOIS, ASSIGNOR TO DIXIE COTTON FELT MATTRESS COMPANY, OF CHICAGO, ILLINOIS, A CORPORATION.

PILLOW.

1,201,554.

Specification of Letters Patent.

Patented Oct. 17, 1916.

Application filed May 7, 1913. Serial No. 766,099.

To all whom it may concern:

Be it known that I, OLIVER M. BURTON, a citizen of the United States residing at Chicago, in the county of Cook and State of Illinois, have invented certain new and useful Improvements in Pillows, of which I do declare the following to be a full, clear, and exact description.

The present invention has for its object 10 to provide a pillow or the like with a strap whereby the pillow may be suspended and which is so disposed that it will not interfere with the snug, smooth fit of the inclosing pillow case.

15 To this end the invention consists in providing the pillow with a strap extending diagonally across the corner thereof, as will hereinafter more fully appear.

Figure 1 is a perspective view of a pillow 20 embodying my invention. Fig. 2 is an enlarged perspective view of one corner of the pillow, parts being shown in section.

The inclosing cover 5 of the pillow comprises, as usual, two pieces of fabric connected at their edges by side and end seams, this cover being filled with any suitable stuffing material 6, such as feathers or the like.

25 Diagonally across the corner of the pillow extends the strap 7, whereby the pillow may be suspended for renovating or otherwise handled. The strap 7 is formed of any suitable stout fabric and may be of one or more thicknesses, two thicknesses of material being shown in the drawing. The strap fits 30 snugly over the rounded surface of the pillow and its ends are inserted between the folded edges 8 and 9 of the side and end

seams of the pillow cover, as clearly shown in Fig. 2, and are united thereto by the rows of stitches 10 by which the folded edges of the pillow cover are connected. It will be understood, of course, that the strap 7 will be united to the pillow when the cover is formed. Inasmuch as the ends of the strap are connected to both side and end seams of the pillow, the strain upon the strap will be most effectively distributed in such manner as to afford the least possible danger of injury to the fabric of which the cover of the pillow is formed and, as the strap snugly 40 engages the outer face of the pillow, it does not interfere with the snug, smooth fit of the pillow case. The strap affords a convenient means by which the pillow may be 45 readily hung up for airing.

Having thus described my invention, what I claim as new and desire to secure by Letters Patent, is:—

A pillow comprising a rounded, stuffed casing formed of two layers of fabric united 50 by side and end seams and a suspension strap extending diagonally across one corner of the pillow, said strap being separate from but snugly fitting over the rounded surface of the pillow and having its opposite in-turned ends interposed between and secured to said layers of fabric at the side and end seams respectively, substantially as described.

OLIVER M. BURTON.
